UNITED STATES PATENT OFFICE.

URSIN L. CUEVAS, OF CUEVAS, MISSISSIPPI.

SPARK-PLUG.

1,334,135.

Specification of Letters Patent. Patented Mar. 16, 1920.

Application filed February 6, 1919. Serial No. 275,279.

To all whom it may concern:

Be it known that I, URGIN L. CUEVAS, a citizen of the United States, residing at Cuevas, in the county of Harrison and State 5 of Mississippi, have invented new and useful Improvements in Spark-Plugs, of which the following is a specification.

My present invention pertains to spark plugs, and particularly to the electrode and 10 insulating structure as embodied in such plugs.

An object of the invention is to provide a spark plug in which the spark gap is between two spaced rings, with which structure 15 firing can take place at any point between the two rings, thus reducing the liability of fouling and allowing for rotation of the spark gap around the rings if perchance any part should become foul.

20 A further object resides in so constructing the central electrode and the insulator core that an absolutely tight joint is accomplished and leakage or loss of compression is absolutely precluded.

25 Yet another object is to arrange, in conjunction with the insulator core and central electrode, a shell which offers maximum protection to the core and at the same time presents a chamber adjacent the electrodes, thus 30 insuring firing of the gas charge.

With these and other objects in view which will be apparent from the drawings in conjunction with the specification and claims, this invention includes certain novel 35 features of construction and combinations of parts which will now be set forth.

In the drawings:

Figure 1 is a view in elevation of a spark plug constructed after the manner of my invention.

40 Fig. 2 is a view in vertical section through the plug.

Fig. 3 is a view in elevation of the sparking end of the plug.

45 Fig. 4 is a perspective view of the central conductor or electrode.

Fig. 5 is an enlarged fragmentary detail view showing a modification of the electrode structure.

50 The shell 1 is threaded at one end as at 2, for securement within the usual spark plug opening, and from this threaded end the central bore is gradually tapered down to about midway of the body portion, where 55 the bore is enlarged to provide a shoulder 3. The remaining end of the shell is made of

polygonal form to take a wrench, and the central bore is enlarged and is internally screwthreaded at 4, a shoulder being formed at 5 at the inner end of the screwthreaded 60 portion.

The insulator core 6 has an axially extending opening 7 therein, and this core which is preferably made of mica is shaped to fit within the bore of shell 1, and an enlarged portion 8 being provided thereon to seat upon shoulder 3, and that portion of the core within the externally threaded end of the shell being reduced to have a chamber entirely therearound.

70 The opening 7 of core 6 is enlarged at the inner end and a shoulder 9 is provided therein, the extreme inner end being widened out in a flare. A central conductor or electrode includes the stem 10 threaded at one end and 75 enlarged at the remaining end with a shoulder 11 formed at the point of enlargement. This enlargement of the stem is at the inner end and the enlargement is of such length that when the stem 10 is fitted into opening 80 7 of the core, shoulder 11 will bear against shoulder 9. At its extreme inner end said stem is widened out into a conical shape conforming substantially to the inner flared end of opening 7, and spokes 12 are formed on 85 the inner extremity of the stem to extend radially therefrom, an electrode ring 13 being carried by said spokes concentrically around the stem.

When the plug is to be assembled a layer 90 of asbestos paper or other fireproof packing 14 is placed around the conical end 15 of stem 10, so that as the stem is inserted into opening 7 a packing is provided between the conical end and the flared portion of 95 the opening. A cap 16 is then placed over the threaded end of stem 10 and is brought down over the outer end of core 6, washer 17 and lock washer 18 then being placed around the stem above cap 16. A clamp 100 nut 19 is next turned onto the threaded end of stem 10, and when turned down will bring the conical portion 15 of said stem to a packing seat against the sheet material at 14, excessive inward movement of the stem 105 sufficient to split the inner end of core 6 being stopped by engagement of shoulder 11 with shoulder 9. Thumb nut 20, of large proportion, is turned onto the threaded end of stem 10 to be used in securing a circuit 110 wire thereto.

From the enlarged portion 8, core 6 is re-

duced in size on a gradual taper toward cap 16, and a lock nut 21 which is externally threaded to fit the threading of the shell at 4 has a tapered bore to receive this tapered portion of core 6 so that when the parts are assembled as shown in Fig. 2, nut 8 will clamp around core 6 to hold the same rigidly in place and will reinforce the same against breaking. Packing gaskets 22 and 23 are placed upon shoulders 3 and 5 so that when the plug is assembled leakage between core and cell is positively precluded.

When the core, carrying the central electrode, is secured in place, electrode ring 13 is positioned at the externally threaded end of shell 1, and as this ring is of less diameter than the bore of the shell a space is provided entirely around the ring. A ground electrode 24, in the form of a ring, is carried at the extreme inner end of shell 1, and this ring 24, which is preferably substantially circular is larger than ring 13 to thus preserve a spark gap between the central electrode and the shell. While the ring 13 and ring 24 may be substantially circular in cross section, these rings might be of the form illustrated in Fig. 5, where angular edges are presented on the inside of ring 24^a and the outer side of ring 13^a.

In use, the parts of my improved spark plug are assembled as shown in Figs. 1 and 2, the diameters of rings 13 and 24 being calculated to give a proper spark gap between the two rings, and ring 13 being spaced evenly and held concentrically within ring 24. The plug is then fitted for use in the usual manner and as the circuit connection to the stem 10 and the grounded shell 1 is established and broken, the current will jump the gap between rings 13 and 24. Where both rings are clean, several fat sparks may pass, and if either ring becomes fouled the spark may be concentrated at one point, however, as the explosion charge is free to flow into the shell around the central electrode, soot and carbon will be blown out with each explosion. Although the plug is self cleaning in the respect as mentioned, if any part of either electrode becomes fouled

the spark will rotate around the rings and it will be seen that clogging of the plug to such an extent that the entire spark gap is closed will be practically impossible.

While, in the foregoing, I have described specific embodiments, and have mentioned only certain possible modifications, it is to be understood that in practice I do not wish to limit myself entirely to the details as herein set forth, but may resort to any practical modifications falling within the scope of the invention as defined in the appended claims.

I claim:

1. A spark plug including with a shell, an insulating core carried within said shell, a central conductor member supported by said core and provided with radially extending spokes at its inner end, said shell having a ground electrode ring of substantially circular cross section formed around the inner end thereof in line with the spokes as the central conductor member is supported by the insulating core, and an electrode ring of substantially circular cross section and carried by said spokes concentrically within and spaced from said ground electrode ring.

2. A spark plug including with a shell, an insulator core mounted in said shell, having an axial opening therethrough enlarged adjacent its inner end and flared at said end, a central conductor having a stem increased in diameter at its inner end and shaped to be of widened out conical form at this extremity, a packing around said conical portion to bear within the flared end of said opening, means to draw the conical portion of said stem against said packing, said central conductor having spokes radiating from the widened conical end thereof, an electrode ring carried by said spokes concentrically around said conductor, and a ground electrode of ring form carried by said shell concentrically around and spaced from said electrode ring.

In testimony whereof, I affix my signature.

URSIN L. CUEVAS.
